UNITED STATES PATENT OFFICE.

JOHN F. TOOMEY, OF NEW YORK, N. Y., AND CHARLES G. SPENCER, OF EAST ORANGE, NEW JERSEY, ASSIGNEES TO AMERICAN TELEPHONE AND TELEGRAPH COMPANY, A CORPORATION OF NEW YORK.

PORTABLE REPEATER APPARATUS.

1,378,919.

Specification of Letters Patent. Patented May 24, 1921.

Application filed March 22, 1919. Serial No. 284,286.

To all whom it may concern:

Be it known that we, JOHN F. TOOMEY and CHARLES G. SPENCER, residing at New York and East Orange, in the counties of New York and Essex and States of New York and New Jersey, respectively, have invented certain Improvements in Portable Repeater Apparatus; of which the following is a specification.

10 This invention relates to telephone systems and more particularly to repeater apparatus adapted to be associated therewith. Conditions often arise in long distance telephony which make it expedient to install 15 telephone repeater equipment temporarily and, on very short notice, in order to give transmission improvement on special or emergency long distance transmission lines. Such conditions would arise where it is 20 planned to install a repeater permanently, but where the need of improvement in transmission is so urgent that it is advisable to employ some temporary method of relief while the permanent installation is being 25 made; or where, because of other proposed changes in switchboard apparatus, it is not desirable to make a permanent repeater installation immediately. Accordingly, a cardinal feature of the invention is the provision 30 of a repeater set suitable for use under such emergency conditions. Another important feature is a repeater set compactly arranged to include all necessary elements such as artificial lines and testing apparatus, 35 so that the set will be complete in itself, will be exceedingly portable, and may be speedily installed at points in a telephone system whenever a sudden need therefor arises. The invention also consists in providing a 40 repeater set suitable for use in connection with any of the usual types of cord circuits at a switchboard and which will utilize the supervisory signaling apparatus of such a cord circuit. Other and further phases of 45 the invention will be clear from the detailed description of the invention.

The repeater set of this invention is mounted in a portable box in which are included the usual coils, artificial lines, potentiometers, relays and other apparatus needed to make the repeater set a complete operating unit itself. Included in the box and associated with the repeater set by means of keys is a testing set for testing the operation

of the repeater. Conductors from the repeater box are wired to one of the usual types of long distance cord circuits at the switchboard. There is also mounted at the switchboard a repeater controlling key associated with relay apparatus in the repeater box. When this key is open a connection is completed through the long distance cord circuit in the usual manner and when the key is thrown the connection is completed through the repeater set. By operating another lever of the repeater key the operator is enabled to connect her monitoring set with the repeater apparatus. Means are provided in the repeater box which are responsive to signaling currents and which serve to operate the supervisory signals associated with the long distance cord circuit.

In the drawing the Figures 1 and 2 when taken together illustrate the circuit arrangements of the preferred form of the invention.

In Fig. 1 of the drawing is shown a type of long distance cord circuit A which is well known in the art. It is understood, however, that the repeater set of this invention is suitable for use with other types of long distance cord circuits. The long distance cord circuit A terminates in the plugs P_1 and P_2 and includes the usual ringing key K_{11} , a splitting key K_{10} , and the monitoring and talking keys K_1 and K_2 respectively. Associated with the keys K_1 and K_2 are the transformers 9 and 11, the relay 10, and the jacks J_3 , whereby the operator's telephone set 12 may be associated with the long distance cord for purposes of monitoring or talking. Included in a bridge across the talking conductors of the cord circuit is the relay 1 which responds to alternating signaling currents and controls the operation of the supervisory signal 5. Included in a bridge across the talking conductors including the high impedance elements 6 is the relay 7 which controls the trunk and toll line supervisory signal 8.

In Fig. 2 is illustrated a circuit diagram of the arrangements contained in the portable repeater box. The plugs P_1 and P_2 of cord circuit A are associated with the cord circuit A and with the repeater set over the contacts of the keys K_3 and K_6 of Fig. 2. Associated with keys K_5 and K_6 is the usual type of two element two way repeater

including the vacuum bulb amplifiers A_1 and A_2 . Associated with amplifiers A_1 and A_2 are the usual potentiometers, condensers, input and output windings and filament circuits. Connected to the input windings of amplifiers A_1 and A_2 are conductors leading to the contacts of key K_8 and then to artificial lines suitable for balancing lines interconnected by the repeater apparatus. 5 Either a plurality of types of artificial lines may be provided suitable for balancing different types of lines to be interconnected, or a single set of artificial lines may be provided as circumstances may require. Associated 10 with other contacts of key K_8 are artificial lines N_1 and N_2 suitable for balancing artificial lines N_3 and N_4 used when the repeater apparatus is being tested. Illustrated in Fig. 1 and preferably mounted 15 at the switchboard is the repeater key K_3 having the levers 13 and 14. When lever 14 is operated the relay 15 responds and connects the operator's telephone set 12 to conductors 16 and to the monitoring coils, 20 which in turn are associated with the amplifiers A_1 and A_2 , thereby allowing the operator to monitor on a connection through the repeater set. The operation of lever 13 serves to operate relay means in the repeater 25 box whereby the filament circuits of amplifiers A_1 and A_2 are closed, the amplifiers are conditioned for operation, the long distance cord circuit A is disconnected from plugs P_1 and P_2 , and the repeater set is 30 connected to said plugs. Associated with the keys K_5 and K_6 are conductors leading to key K_7 and to apparatus for testing the repeater set. Included in these conductors are the artificial lines N_3 and N_4 adapted to 35 simulate lines between which connections would be made by the repeater set under actual conditions. Associated with key K_7 are conductors leading to key K_{12} upon the operation of which a tone current or a signal- 40 ring current may be transmitted through the amplifiers for testing purposes. Associated with the contacts of key K_7 are conductors leading to a telephone receiver, with which is associated a receiver shunt 82 including 45 a variable series resistance 18 and a variable shunt resistance 17. Associated therewith is the key K_9 which serves to close a shunt about resistance 18 and also serves to disconnect the repeater set from the testing 50 apparatus and to connect the cord circuit A in place thereof.

The invention may now be more fully understood from the following description of its operation:

60 If a connection is established between two long distance lines by means of the cord circuit A, a talking circuit between said lines will be completed as follows: from the talking conductors of the line associated 65 with plug P_1 over the contacts of plug P_1 ,

conductors 27, contacts of key K_5 , conductors 28, conductors 29, over the talking conductors of the cord A, over conductors 30, conductors 31, contacts of key K_6 , conductors 32, contacts of plug P_2 and thence over 70 the talking conductors of the line associated with plug P_2 . Ground will also be applied from the sleeve conductor of the line associated with plug P_1 over the sleeve contact of plug P_1 , sleeve conductor of plug P_1 , 75 contact of key K_5 , conductor 33, armature and contact of relay 36, conductors 34 and 35, winding of relay 4, to battery and ground. The closing of this circuit will operate relay 4 and close the following circuit: 80 from ground and battery, armature and contact of relay 4, conductors 83, 84, and 49, winding of relay 2, contact and armature of relay 1, to ground. The closing of this last mentioned circuit will operate relay 2 which 85 by pulling up its armature will prevent the relay 3 from being energized and the supervisory signal 5 from functioning as will be pointed out later.

The operator by now throwing her listening key K_1 may connect her telephone set 12 to the talking conductors of the cord A. The operation of key K_1 , closes the following circuit: from ground, contact of key K_1 , conductor 20, winding of relay 10, to battery and ground. The closing of this circuit will operate relay 10 which will pull up its armatures and connect the operator's telephone set 12 to the talking conductors of cord A as follows: from the talking conductors of cord A, contacts of key K_1 , conductors 19, windings of transformer 9, conductors 21 and 22, armatures and contacts of relay 10, conductors 23, conductors 24, 90 contacts of jacks J_3 and plugs P_3 , to operator's telephone set 12. If the operator ascertains that the connection is one which may be completed without the use of repeater apparatus, the connection will be completed between the lines over the cord 100 circuit A in the usual well known manner which will not be described. However, if the operator finds that the connection is one in which it is desirable to employ repeater apparatus, the operator will throw lever 13 105 of the repeater key K_3 . Upon the operation of lever 13 the following circuits will be closed: from ground and battery, conductor 47, contact of key K_3 , conductor 48, to junction point 49; from junction point 49, over conductor 50, winding of relay 38, to ground; from junction point 49, over conductor 51, to junction point 52; from junction point 52, about the winding of relay 37, over conductor 54, contact and armature of relay 45, conductor 55, contact and armature of relay 46, to ground; and from junction point 49, over conductor 63, winding of relay 44, to ground. The closing of 110 these circuits will energize the relays 38, 36, 115 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715

37, and 44. Upon the energization of relay 37 a circuit will also be closed from junction point 52 through the winding of relay 36, conductor 53, contact and armature of relay 5 37 to ground thereby operating relay 36.

Upon the operation of relay 36 the following circuit will be closed: from ground applied to the sleeve conductor of the line associated with plug P_1 , over the sleeve contact of plug P_1 , sleeve conductor of plug P_1 , contact of key K_5 , conductor 33, armature and contact of relay 36, conductor 56, winding of relay 39, to battery and ground. The operation of relay 36 will also close the following circuit: from ground applied to the sleeve conductor of the line associated with plug P_2 , sleeve contact of plug P_2 , sleeve conductor of plug P_2 , contact of key K_6 , conductor 57, armature and contact of relay 20 36, conductor 58, winding of relay 40, to battery and ground. The closing of these two last mentioned circuits will operate relays 39 and 40. The operation of relay 39 closes the following circuit: from ground and battery, winding of relay 41, conductor 59, armature and contact of relay 39, conductor 60, winding of relay 42 to ground. The operation of relay 40 closes the following circuit: from ground and battery, 25 winding of relay 41, conductor 61, armature and contact of relay 40, conductor 62, winding of relay 43, to ground. The closing of these two last mentioned circuits will energize the relay 41 and the relays 42 and 43. The operation of relay 41 serves to open 30 short circuits across the input paths of amplifiers A_1 and A_2 which, together with the aforementioned operation of relay 44, which closes the filament circuits for said amplifiers, will condition the amplifiers for operation. The operation of relays 42 and 43 35 serve to disconnect conductors 29 and conductors 30 from conductors 28 and conductors 31, respectively, and connect the circuits of the amplifiers A_1 and A_2 to conductors 28 and conductors 31; thereby disconnecting the cord circuit A from said conductors and substituting the repeater apparatus therefor.

Upon the energization of relay 36 the 40 previously traced circuit about the winding of relay 4, which controlled the supervisory apparatus associated with cord A, will be opened. However, a circuit for the relay 4 will be completed upon the operation of relay 38 as follows: from ground and battery, winding of relay 4, conductors 35 and 34, conductor 64, contact and armature of relay 38, conductor 65, conductor 66, resistance 45 elements 67, to ground. Accordingly, when the repeater set is substituted for the cord circuit A, the relay 4 will still remain energized and the supervisory apparatus under its control will still be available for use.

The operation of relay 38 by means of its

upper armature and contact also serves to maintain the relay 68 and the supervisory apparatus associated with the other end of cord A in a condition for operation. A talking circuit between the transmission lines 50 will now be completed through the repeater set as follows: from the talking conductors of the line associated with the plug P_1 , contacts of plug P_1 , conductors 27, contacts of key K_5 , conductors 28, contacts and armatures of relay 42, over input and output circuits of amplifier A_1 , armatures and contacts of relay 43, conductors 31, contacts of key K_6 , conductors 32, contacts of plug P_2 , and over the talking conductors of the line 55 associated with plug P_2 .

If, when a connection is established between two long distance lines by means of the cord circuit A, signaling current is transmitted from the line associated with plug P_1 such signaling current will be transmitted over the tip and ring contacts of plug P_1 , conductors 27, contacts of key K_5 , conductors 28, conductors 29, talking conductors of cord A, and thence over conductors 69 bridged across said talking conductors, and about the windings of relay 1. As the relay 1 is responsive to alternating ringing currents of the type which would be transmitted from such a line it will respond thereto and open the circuit formerly closed through the relay 2, thereby deenergizing relay 2. Upon the deenergization of relay 2, the following circuit will be closed: from ground and battery, armature and contact of relay 4, conductors 83 and 84, winding of relay 3, conductor 70, contact and armature of relay 2, conductors 71, 72 and 73, contact of key K_2 , conductor 74 to ground. If the splitting key K_{10} and the talking key K_2 60 should both be opened at this time, this last mentioned circuit will be completed as follows: from conductor 72, contact of key K_{10} , over conductor 75, to ground. The closing of this circuit will operate the relay 3 which will pull up its upper armature and will become locked up over its upper contact and armature. The operation of the relay 3 will also close the following circuit for the supervisory lamp 5; from ground and battery, armature and contact of relay 4, conductor 83, filament of signal lamp 5, conductor 76, contact and armature of relay 3, over conductor 72 and thence to ground as previously pointed out.

If, when a connection is established between two long distance lines and the repeater set is being used in place of the cord circuit A, ringing current coming in over one of the long distance lines, such as the line associated with plug P_1 , will be transmitted over the following path: from the talking conductors of the line, over the tip and ring contacts of plug P_1 , over conductors 27, contacts of key K_5 , conductors 28, 70

and thence over conductors 77 bridged across conductors 28, and through the windings of the relay 45. As the relay 45 is responsive to ringing currents of this type, it 5 will pull up its armature and open the circuit formerly completed upon the operation of lever 13 of the repeated key K_3 through the winding of relay 37. The opening of this circuit will deenergize relay 37 which 10 will, in turn, cause the deenergization of relay 36, of relays 39 and 40 and of relays 42 and 43. The deenergization of relays 42 and 43 will disconnect the repeater apparatus from conductors 28 and 31 and will connect said conductors to conductors 29 and 30 respectively. The ringing current coming in from the line will now be transmitted over conductors 29 to the cord circuit A and will operate the supervisory means associated therewith in the manner previously pointed out. Bridged across conductors 31 is the relay 46 similar to the relay 45 and which will respond to ringing currents coming in over a long distance line associated 25 with the plug P_2 , and which will serve in a manner similar to the relay 45 to cause the repeater set to be disconnected from conductors 31 and will connect conductors 30 to conductors 31 so that the ringing currents 30 will operate the supervisory means in the cord A.

If a connection is established between two long distance lines and the repeater set is being employed in connection with the cord 35 circuit A, the operator, if she desires to monitor on such a connection, will throw lever 14 of the key K_3 . This will close the following circuit: from ground and battery, contact of key K_5 , conductor 78, winding of 40 relay 15 to ground. This will operate relay 15 and connect conductors 24 leading to the operator's telephone set 12 to the conductors 16. The conductors 16, in turn, are connected to conductors 79 and 80 which are 45 inductively related to the monitoring windings of the vacuum bulbs A_1 and A_2 respectively. Accordingly by operating the lever 14, the operator will be enabled to monitor on a connection made through the repeater 50 set.

If it is desired to test the apparatus of the repeater set, the keys K_5 and K_6 are thrown and the conductors 28 and 31 are disconnected from the conductors leading to plugs 55 P_1 and P_2 respectively and are connected to conductors 90 and 91 leading to the testing apparatus. Lever 13 of the repeater key K_3 is also thrown and the repeater set is thereby connected to conductors 28 and 31 in a manner similar to that already pointed out except that the circuits controlling relays 39 and 40 will now be completed as follows; from ground and battery, winding of relay 39, conductor 56, contact and armature of 60 relay 36, conductor 33, contact of key K_5 ,

conductors 97 and 98, contact of key K_6 , conductor 99, to ground; and from ground and battery, winding of relay 40, conductor 58, contact and armature of relay 36, conductor 57, contact of key K_6 , conductor 100, conductor 98, contact of key K_6 , conductor 99, to ground. The key K_9 is now thrown and the above traced circuits through relays 39 and 40 are opened at the contact of key K_9 . Upon the deenergization of relays 39 and 40 70 the repeater set is disconnected from conductors 28 and 31 and conductors 28 and 31 are connected to conductors 29 and 30 respectively leading to the cord circuit A. The key K_{12} will now be thrown and either 75 a source of ringing current or of tone current may be applied to conductors 92. This testing current will be transmitted over the following path: from conductors 92, contacts of key K_7 , conductors 90, contacts of key K_5 , conductors 28, conductors 29, over the talking conductors of cord circuit A, conductors 30, conductors 31, contacts of key K_6 , conductors 91, contacts of key K_7 and thence over conductors 95 and 96, and the short 80 circuit formed by contact of key K_6 to the telephone receiver. After observing the quality of the tone in the receiver, the key K_9 is restored to normal again. This will complete the formerly traced circuits for 85 relays 39 and 40 which upon becoming energized will cause the repeater set to be connected to conductors 28 and 31 and will disconnect conductors 29 and 30 from conductors 28 and 31 respectively, as has been 90 formerly pointed out. The testing current applied to conductors 92 by the aforementioned operation of key K_{12} will now be transmitted over the following path: from conductors 92, contacts of key K_7 , conductors 90, 105 contacts of key K_5 , conductors 28, through the repeater set, over conductors 31, contacts of key K_6 , over conductors 91, contacts of key K_7 , over conductors 95 and 96, and through the receiver shunt 18, to the telephone receiver. The receiver shunt will now 110 be adjusted until the quality of the sound heard in the receiver is the same as in the case when the testing current was transmitted through the cord circuit A. The reading on the indicating means of the receiver shunt will now show the transmission gain 115 due to the including of the repeater apparatus in the circuit. It is to be noted that when the repeater apparatus is being thus 120 tested the key K_8 should be operated so that the networks N_1 and N_2 suitable for balancing the artificial lines N_3 and N_4 may be associated with the amplifiers A_1 and A_2 respectively. Furthermore by operating the key 125 K_7 , the testing current may be transmitted through the repeater set or the cord circuit A in either direction desired.

While the invention has been disclosed as embodied in certain specific arrangements 130

which have been deemed desirable, it is to understood that it is capable of embodiment in many and widely varied forms without departing from the spirit of the invention 5 as defined in the appended claims.

What is claimed is:

1. In a telephone system, a cord circuit for interconnecting transmission lines, supervisory signaling apparatus associated with 10 the terminal arrangements of said cord circuit, means responding when one of said terminal arrangements is associated with a transmission line for rendering said supervisory signaling apparatus in a condition 15 for operation, a repeater set associated with the terminal arrangements of said cord circuit, switching means whereby said cord circuit may be disconnected from said terminal arrangements and said repeater set may be 20 connected to said terminal arrangements, and means in said repeater set responding when said cord circuit is disconnected from said terminal arrangements for maintaining said supervisory signaling apparatus in a 25 condition for operation.
2. In a telephone system, a cord circuit for interconnecting transmission lines, supervisory signaling apparatus associated therewith, a repeater set associated with the 30 terminal arrangements of said cord circuit, switching means whereby said repeater set may be connected to said terminal arrangements in place of said cord circuit, means in said repeater set responsive to signaling cur- 35 rents when said repeater set is connected to said terminal arrangements for connecting said cord circuit to said terminals in place of said repeater set.
3. In a telephone system, a cord circuit for

interconnecting transmission lines, supervisory apparatus associated therewith and responsive to signaling currents transmitted over said lines when said lines are interconnected by said cord circuit, a repeater set for interconnecting said lines independently of said cord circuit, relay means in said repeater set and responsive to signaling currents transmitted over said lines when said lines are interconnected by said repeater set, and means controlled by said relay means for causing said supervisory apparatus to be operated. 40 45 50

4. A cord circuit located at a switchboard, supervisory apparatus associated with the terminal arrangements of said cord circuit, 55 means responding when one of said terminal arrangements is associated with a transmission line for rendering said supervisory apparatus in a condition for operation, a repeater set included in a portable box and 60 adapted to be located in a position separate from said switchboard, means for associating said repeater set with the terminal arrangements of said cord circuit, switching means at said switchboard whereby said 65 cord circuit may be disconnected from said terminal arrangements and said repeater set may be connected to said terminal arrangements, and relay means in said portable repeater box responding when said cord circuit is disconnected from said terminal arrangements for maintaining said supervisory apparatus in a condition for operation. 70 75

In testimony whereof we have signed our names to this specification this 20th day of March, 1919.

JOHN F. TOOMEY.

CHARLES G. SPENCER
